APPARATUS FOR DETERMINING THE PERCENTAGE, BY WEIGHT, OF LINTERS, ON COTTONSEED

Charles Scott Shaw, Leland, Miss.; dedicated to the free use of the People of the United States of America

Application June 29, 1938, Serial No. 216,594

4 Claims. (Cl. 83—93)

(Granted under the act of March 3, 1883, as amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to me of any royalty thereon.

I hereby dedicate the invention herein described to the free use of the people of the United States of America to take effect on the granting of a patent to me.

My invention relates to the art employed in laboratories for removing linters from cottonseed by the acid-fuming method, and has for its general object the provision of a method and apparatus for accurately determining the percentage, by weight, of the linters contained in a sample of cottonseed.

My invention is an improvement in the acid-fuming method of determining the percentage of linters on cottonseed, and provides an effective and simple mechanical apparatus for brushing and sieving several samples of cottonseed simultaneously, in lieu of brushing, rubbing, and sieving each sample manually. It also provides a novel and useful means for removing the linter residue, following completion of the sieving process, from the containers used beneath the sieves during the process of sieving; and it permits the retention of all of the seed coat fragments in the containers, after which said fragments can be combined with the delinted seed for weighing in order to determine more accurately than has heretofore been possible, the weight of the delinted seed for comparison with the weight of the original sample of cottonseed prior to delinting. The removal of the linter residue from the containers is accomplished without disturbing the seed coat fragments.

An important feature of the present invention resides in the small number of elements and their extreme simplicity, which makes it practical and available for the simultaneous determination of the linters on a plurality of samples of cottonseed.

The following description together with the accompanying drawing will disclose my invention more fully, and further objects and advantages thereof will be apparent.

In the drawing:

Figure 1 is a diagrammatic side elevation of my device.

Figure 2 is a plan view of the sieve pan holder.

Figure 3 is a partial sectional plan view of one of the sieve pans.

Figure 4 is a cross-sectional view along the line 4—4 of Figure 2.

Referring with more particularly to the accompanying drawing, in which like numerals designate like parts throughout the several views; the numeral 1 designates a belt drive, (source of power not shown) driving a plurality of entrained pulleys 2 by means of the belt 3. The vertical spindles 4, driven by said pulleys 2, extend through and are supported on the horizontal beam 5 of the inverted U-shaped bearing-support 6 by means of suitable bearings 2A. Said spindles support the horizontally disposed slotted brush-holder bars 7 which are adjustably secured to the spindles by means of the sleeves 8A and the thumbscrews 8. The stanchions 9 of the bearing-support 6 are provided with suitable base support 10, such as ordinary channel iron. The brushes 11, having bristles of suitable acid resisting material, are adjustably connected to the brush-holder bars 7 by means of the shouldered bolt and wing nut assemblies 12 positioned within the slots 13 of brush-holder bars 7 and the slots 14 of brush bars. By these means an orbital motion is imparted to the brush bristles, concentric with and in juxtaposition to the spherical inner surfaces of the hemispherical sieves 15 upon rotation of the spindles 4. The hemispherical sieves 15, of suitable acid resisting material, are suspended and removably secured in the cylindrical sieve pans 16, also of acid resisting material, by means of outwardly extending flange members 17 resting on the upper edges of said sieve pans 16, and in frictional contact between portions of the outer surfaces of sieves 15 with the upper inner side wall surfaces of the pans 16. The sieve pans 16 are provided at their lower bases with outwardly extending flanges 18 having notches 19 formed therein for engagement with the substantially semi-circular undercut recesses 20 and pins 21, respectively, of the split sieve pan holder 22 (Fig. 2). The sieve pan holder 22 consists of two flat bar members 23 and 24, provided with the oppositely disposed substantially semi-circular notches 25 and undercut recesses 20 concentric thereto, the pins 21, the hinges 26, and it is adapted to secure and removably retain the sieve pans 16 in position beneath the brush-holder bars 7. The member 23 of the pan holder 22 is firmly attached to the rear on the upper surface of the pan support shelf 27 which is secured at its ends 28 and 29 to the stanchions 9. The hinged member 24 of the pan holder 22 is held in position forward of the fixed member 23 on the upper surface of the

pan support shelf 27 by means of the hinges 26 fastened to the pan support shelf.

In practice my invention may be employed, following the customary laboratory procedure of exposing the sample of cottonseed to the action of acid in porous fuming pots, by transferring the treated masses of cottonseed to the sieves 15 suspended in the sieve pans 16, then inserting the sieve pans within the semi-circular notches 25 of the pan holder member 23 so that the pan flanges 18 lie within the semi-circular recesses 20 and the pins 21 are in engagement with the flange notches 19. The pan holder hinged member 24 is then lowered into position, thereby securing the sieve pads in operating position beneath the brush holders 7. The brush holders 7, being fitted to the spindles 4, are adjusted vertically for the approximately desired depth of the brushes 11 within the sieves 15 by manipulation of the thumbscrews 8. The final adjustment of the brushes 11, vertically for depth and horizontally for eccentricity with respect to the center of the sieves, is accomplished by manipulation of the shouldered bolt and wing nut assemblies 12 within the slots 13 and 14. The process of brushing the linter residue from the acid treated cottonseeds is accomplished by rotating the brush assembly 7, 11, 12, when properly set, at a moderate rate of speed so that the bristles of the brushes will cause the various seeds to ride part way up the hemispherical inner surfaces of the sieves 15 in an irregularly rolling motion only to drop back again to the bottom of the sieves where they will again be caught up in the motion of other seed and the process repeated. The combined brushing and scrubbing action of the cottonseed by the brush bristles and inner surfaces of the sieves is continued until the acid treated seed are freed of all the linter residue which in turn pass through the sieves together with fragments of cottonseed coat, resultant to the agitation, and are collected in the sieve pans 16, the delinted samples of cottonseed remaining in the sieves 15. After the brushing and sieving process is completed, the sieve and pan units are removed from the pan holders. The mixture of linter residue and seed coat fragments remaining in the sieve pans is separated by winnowing out the linter residue, thus retaining the seed coat fragments intact in the sieve pans for subsequent combination with the respective delinted seed for weight determinations. The separation of the linter residue from the seed coat fragments is accomplished by gently shaking a sieve pan and its contents in a rotary motion in an induced current of air, such as may be derived from an electric fan, so that the agitation of the contents exposed to the air currents will cause the relatively light linter residue to be blown out of the sieve pan—the heavy

seed coat fragments remaining intact in the sieve pan.

Following the above described operations, the customary laboratory procedures for determining the percentage of linters on cottonseed by weight may be resumed.

It should be understood that variations in construction of the spindles, and the brushes, or in the proportion of the sieves, pans, and other parts, may be effected without departing from the spirit of my invention; and that my invention may be used in connection with any adaptable acid-fuming method.

Having thus described my invention, I claim:

1. An apparatus of the character described comprising a frame structure, a table secured to said structure, means on said table for removably securing a cylindrical container, a substantially hemispherical sieve removably secured through the top of said container, a brush disposed in contact with said sieve eccentric to its vertical axis, means for revolving said brush about said axis, and means for adjusting the eccentricity of said brush with respect to said axis. 15

2. An apparatus of the character described comprising a frame structure, a table secured to said structure, means on said table for removably securing a cylindrical container, a substantially hemispherical sieve removably secured through the top of said container, a brush disposed in contact with said sieve eccentric to its vertical axis, means for revolving said brush in a path concentric to said axis, and means for adjusting the eccentricity of said brush with respect to said axis. 20

3. An apparatus of the character described comprising a frame structure, a table secured to said structure, means on said table for removably securing a cylindrical container, a substantially hemispherical sieve removably secured through the top of said container, a brush disposed in contact with said sieve eccentric to its vertical axis, means for revolving said brush about said axis, means for adjusting the eccentricity of said brush with respect to said axis, and means for adjusting said brush on the surface of said sieve in selected positions of eccentricity. 40

4. An apparatus of the character described comprising a frame structure, a table secured to said structure, means on said table for removably securing a cylindrical container, a substantially hemispherical sieve removably secured through the top of said container, a brush disposed in contact with said sieve eccentric to its vertical axis, means for revolving said brush in a path concentric to said axis, means for adjusting the eccentricity of said brush with respect to said axis, and means for adjusting said brush on the surface of said sieve in selected positions of eccentricity. 50

CHARLES SCOTT SHAW.
